Thomas A. Hill

UNITED STATES PATENT OFFICE.

WILLIAM J. SNADECKI, OF WESTOVER, VIRGINIA, ASSIGNOR TO RICHARD CRANE.

RUDDER FOR BOATS.

Application filed August 28, 1924. Serial No. 734,696.

My invention relates to improvements in means for correcting the whirling motion of the water set up by the revolving of a marine propeller, and more particularly has reference to vanes, plates, or planes aft of the propeller against which the whirling water strikes and by which it is more or less straightened out. Due to the pitch of the blades of a propeller the water set in motion thereby naturally whirls in corkscrew-like fashion creating considerable disturbance proportionate to the energy applied, and considerable percentage of which is wasted due to the fact that it is expended more or less laterally instead of directly astern.

One of the principal objects of my invention is to correct or minimize as much as possible this lateral disturbance of the water so as to thereby increase the thrust or bite of the propeller and its effective forward effort against the water.

In the accompanying drawings, I have illustrated in Fig. 1, the stern of a boat with vanes or blades upon the rudder, thus embodying an application of my invention. Fig. 2 is a side elevation of a suitable form of rudder showing the application of two vanes preferably curved. Fig. 3 is a similar view showing an arrangement of three vanes, and Fig. 4 is a plan view looking down upon the rudder.

5 is the hull of the boat, 6 the propeller thereof, 7 the rudder, and 8 the rudder post. 9, 10 indicate two vanes or planes, one on each side of the rudder. These are preferably curved as shown and follow immediately

in the wake of the propeller. These vanes ride against and upon the disturbed water, tending to iron out or smooth the same, 40 thereby reducing the disturbance and keeping the water more solidly behind the working surfaces of the propeller. In Figs. 2 and 3, I have shown two and three vanes respectively, and of course it will be readily understood that any number of vanes may be employed and may be positioned and formed in various ways as may be found desirable. In small boat construction, these vanes and planes also serve as a planing surface which 45 becomes more and more effective as the bow lifts when under speed. By this method of smoothing out the lateral agitation of the water, the effort of the screw is more effective and works against a denser medium, 50 thereby increasing the speed with a given output of energy. The blades also tend to have a steadyng effect and tend to minimize the rocking of the boat on its transverse axis.

Of course it will be understood that various modifications may be made in the construction and arrangement of parts without departing from the spirit of the invention as claimed.

I claim:—

In combination with the rudder of a self-propelled vessel, vertically spaced vanes projecting laterally from both faces thereof, 70 said vanes curved about a transverse axis.

In testimony whereof I hereunto affix my signature.

WILLIAM J. SNADECKI.
